UNITED STATES PATENT OFFICE.

GEORGE W. WILLARD, OF DETROIT, MICHIGAN.

DESIGN FOR A PICTURE-HOOK.

SPECIFICATION forming part of Design No. 26,837, dated March 30, 1897.

Application filed January 11, 1897. Serial No. 618,883. Term of patent 14 years.

To all whom it may concern:

Be it known that I, GEORGE W. WILLARD, a citizen of the United States, residing at Detroit, county of Wayne, State of Michigan, 5 have invented and produced a new and original Design for a Picture and Picture-Hook Hanger, of which the following is a specification, reference being had to the accompanying drawings, showing a part thereof.

10 Figure 1 of the drawings is a view in elevation of a picture and picture-hook hanger, showing my design. Fig. 2 is a cross-section of the arm B.

The leading features of my design consist 15 in a shank formed with an upright portion and an offset portion at its upper end, the offset portion supporting thereupon two arms spaced one from the other at their upper ends and united intermediate their ends by a seat 20 of circular outline, the curved seat resting upon the upper end of the shank.

Accordingly A represents the upright portion of the shank, and A' the offset portion.

B and B' represent the two arms, united at their lower ends by the seat B², of circular 25 outline, said seat resting upon the upper end of the shank. The contour of the arms B B', which are spaced apart, meet at their lower ends in the curved seat B². The contour of the arms and seat thus present to the eye the 30 combined effect of a circular seat projecting upward at its extremities, forming the spaced arms B B', said arms and seat supported upon the upper end of the offset portion of said shank. 35

What I claim is—

The design for a picture and picture-hook hanger, substantially as herein shown and described.

In testimony whereof I sign this specification in the presence of two witnesses. 40

GEORGE W. WILLARD.

Witnesses:

GEORGE W. KEELEY,
N. S. WRIGHT.
